Des. 233,176
Patented Oct. 8, 1974

233,176

COMBINED CIGARETTE LIGHTER, DESK PEN AND TRAY

Samuel J. Koch, % Korex Industries, 821 Malcolm Road,
Burlingame, Calif. 94010

Continuation-in-part of design application Ser. No.
211,838, Dec. 23, 1971. This application Nov. 9,
1972, Ser. No. 304,957

Term of patent 14 years

Int. Cl. D19—02
U.S. Cl. D74—5 B

FIG. 1

FIG. 2

FIG. 4

FIG. 3

FIG. 1 is an exploded top perspective view of a combined cigarette lighter, desk pen and tray showing my new design;

FIG. 2 is a left side elevational view thereof on a reduced scale;

FIG. 3 is a bottom plan view thereof on a reduced scale;

FIG. 4 is a rear elevational view thereof on a reduced scale.

This application is a continuation-in-part of my co-pending application Serial No. 211,838, filed Dec. 23, 1971 for cigarette lighter.

I claim:

The ornamental design for a combined cigarette lighter, desk pen and tray, as shown and described.
